UNITED STATES PATENT OFFICE

115,353

DESIGN FOR A BATTERY SERVICE KIT OR THE LIKE

Joseph C. Thomas, Akron, Ohio, assignor to E.
Edelmann & Co., Chicago, Ill., a corporation of Illinois

Application November 8, 1938, Serial No. 80,964

Term of patent 14 years

To all whom it may concern:

Be it known that I, Joseph C. Thomas, a citizen of the United States, residing at Akron, in the county of Summit and State of Ohio, have invented a new, original, and ornamental Design for a Battery Service Kit or the like, of which the following is a specification, reference being had to the accompanying drawing, forming part thereof, and in which:

Figure 1 is a view in perspective looking downwardly and toward one corner of my battery service kit or the like.

Fig. 2 is a view similar to Figure 1 looking toward another corner.

Fig. 3 is a top plan view.

The side opposite that shown in Figs. 1 and 2 is substantially the same.

I claim:

The ornamental design for a battery service kit or the like, as shown and described.

JOSEPH C. THOMAS.
